STARTING GATE

Octave Blake, Plainfield, N. J.

Application March 11, 1947, Serial No. 733,845

8 Claims. (Cl. 119—15.5)

1

This invention relates to a starting barrier or starting gate for equally aligning contestants at the start of competitions of speed. The broad principle of the invention is subject to numerous modification and adaptations but for the sake of clarity the invention will be described in one of its modifications as employed in aligning the contestants at the start of harness or sulky races.

The present methods employed at the start of contests of speed include the locating of a contestant in an immovable position, making it necessary for the contestant to overcome the inertia of starting and allowing other contestants to be in more favorable positions at the actual instant of the start, because of the possible degree of their relaxed or tensed attitudes. Such contests of speed are not true speed contests but are the sum of the time, involving the rate of speed required to overcome the inertia of starting, the rate of speed required to assume a particular starting position, and subsequently the rate of speed required to travel across a specified distance.

In order to overcome the retarding or slowing effect of the actual start of a contest of speed, some contests, such as trotting, harness, or sulky racing and automobile racing employ a moving or running start. In contests employing the moving or a running start, considerable difficulty is encountered in properly aligning the contestants as they actually cross the starting line. Thus a fast starting contestant may be given an apparent advantage by being slightly ahead of the balance of the contestants traveling at a slower rate of speed at the instant that the starting line is crossed. The slower rate of speed of a contestant may be caused by a retarding of the contestant's actual speed in an effort to allow the balance of the contestants to come into a substantial alignment. A slow starting contestant may be at an apparent disadvantage in being slightly behind the contestants but, at the instant of crossing the starting line the slow starting contestant may be traveling at a greater speed than the balance of the contestants. In this latter case, the increased speed of this contestant may be caused by his increasing his speed to come into a substantial alignment with the balance of the contestants.

It will thus be apparent that at the instant of crossing the starting line the forwardmost contestant may be placed at a disadvantage while the trailing contestant may obtain a definite advantage.

For the above and other reasons, the starter

2

of such a contest of speed must not only see that the contestants are properly aligned but also must take into consideration the actual favorable or unfavorable position of each individual contestant. For this reason it sometimes occurs in the start of a harness race that the starter will recall the contestants for additional starts even though, to the spectators the contestants were properly aligned.

10 The restarting of such racing is not only irritating to the spectators and to the drivers but also appears to have a discouraging effect on the contestants themselves, appearing to cause very erratic results of the races.

15 Other difficulties and disadvantages of the present methods of starting of a race are well known and may include the favoring of a contestant by the starter of the race.

It is an object of the present invention to provide a more equitable alignment of the contestants at the start of contests of speed.

It is another object of the invention to eliminate the restarting of contests of speed.

It is a further object of the invention to substantially reduce at the start of a race one contestant's advantages over that of another.

The above and other objects and advantages of the invention will be apparent from the following detailed description taken with reference to the accompanying drawings in which:

30 Figure 1 is a top view of a mechanically operated starting device mounted upon an automobile trailer according to the invention.

Figure 2 is a rear view of the device of Figure 1 as viewed by the contestants at the start of a contest of speed.

35 Figure 2A shows the trailer and starting barrier attached to a self-propelled automotive vehicle;

40 Figure 2B shows a starting barrier according to the invention directly mounted upon a self-propelled automotive vehicle;

Figure 3 is a top view of the device of Figure 1 with the seat and floor removed.

45 Figure 4 is a sectional view of the device of Figure 2 taken along the line 4—4 of Figure 3.

Figure 5 shows a modification of the mechanism according to Figure 3.

Figure 6 is a cross section of a portion of the telescopic arms of Figure 1 at one of the joints.

Figure 7 illustrates diagrammatically a pneumatically operated starting barrier embodying the principles of the invention.

Like reference numerals identify the same parts throughout the different views of the drawings.

The starting barrier or starting gate according to the invention comprises essentially one or more telescoping arms, mechanism for retracting subsequent sections of the telescoping arms within each other and a movable carrier, such as a trailer 20, Figure 2A, or an automotive vehicle 20', Figure 2B, to which the telescoping arm and mechanism may be attached.

Referring more specifically to the drawings, there is shown in Figures 1 and 2 an automobile trailer 20 having a suitable trailer hitch 21 and adapted with a portion 22 in which is provided a seat 23. The portion 22 is provided with a floor 24 which also serves as a cover for the operating mechanism later to be described.

The trailer hitch 21 is adapted for engagement with a movable means such as an automotive vehicle 20', truck or the like, as shown in Figure 2A. The trailer is provided with the conventional pneumatic tired wheels 25 and may be provided with a loud speaker 26 which is part of a public address system (not shown) for instructing the contestants during the start of the contest.

Attached to the rear of the trailer and at the proper height, with respect to the contestants, is a telescoping arm 30 consisting of an outside tube 31 which is attached to the back of the trailer by brackets or by welding and interfitting tubes 32, 33, 34, 35 and an interfitting central core or tube 36.

The core or tube 36 is provided at its outer end with a disc or stop 37 of sufficient diameter to entirely cover the ends of the tubes 32, 33, 34, 35, 36 and being of sufficient diameter to serve as a stop against the end of the tube 31. In a similar manner and located slightly below the tube 31 there is also secured horizontally to the back of the trailer 20 a telescoping arm 30' consisting of a tube 31' having an identical set of interfitting tubes 32', 33', 34', 35', and an identical center core 36' and stop 37'. The telescoping tube assembly 30 is mounted horizontally on the back of the trailer 20 in such a manner that the interfitting telescoping tube and core arrangement can be extended to the right and the telescoping tube arrangement 30' is mounted horizontally on the back of the trailer 20 in such a manner that it can be extended to the left. Alternatively, the telescoping arms may be directly mounted upon the rear of the vehicle 20', as shown in Figure 2B.

The telescoping tube assemblies 30 and 30' can be chosen of such a length and number of sections as to extend completely across the racing track and thus, if placed at the proper height on the back of the trailer or vehicle, they will serve as a barrier for the contestants. It will be apparent that the telescopic tube can be extended to any desired distance less than the maximum extension of the telescoping arms, i. e. if the starting barrier is used on a wide track the arms may need to be extended to their maximum extension, and if the starting barrier is used on a narrow track the arms may be extended to just the amount required. It will also be apparent that if only a few contestants are engaged in the race, or if the track is narrow, only the extension of one telescoping arm would be required. Thus, the length of the barrier can be adjusted in accordance with the width of the track or the number of contestants.

The telescoping arm assembly 30 is mounted horizontally on the trailer in such a manner that the right end of the arm assembly is substantially flush with the right side of the trailer when the

tubes are collapsed and also mounted in such a manner that a free space 40 is provided at the left end of the tube assembly 31. In the back of the trailer and within the free space 40 there is provided a horizontal slot 41 extending through the back wall of the trailer. Positioned horizontally in the slot 41, and journaled in suitable bearings, there is provided a pulley wheel 42. Similarly, the telescoping tube assembly 30' is mounted horizontally in such a manner that when the tubes are telescoped the left end of the tubes will be substantially flush with the left side of the trailer 20 and also that a space 40' is provided at the right end of the tubes. There is also provided a horizontal slot 41' extending through the back end of trailer and a similarly journaled pulley wheel 42'.

The telescoping arms 30 and 30' when extended may be required to reach substantially across the track and may thus be required to cover a distance of the order of 80 to 100 feet, and when so extended the ends of the arms may sag slightly because of the weight thereof; furthermore such a sag or bending of the arms may increase the friction of the telescoping tube sections 31 to 36 and 31' to 36', thus making it difficult to retract the arms. The sagging effect of the arms can be compensated for by attaching the tubes 31 and 31' slightly out of the horizontal position with the extending ends slightly elevated.

In order to overcome the friction encountered by the bending of the extending tubes there is shown in Figure 6 a typical section joint employing ball bearing sliding portions. The outside tube 33 has attached to the inside at the right end a ball bearing 45 secured to the tube 33 by welding, brazing, or the like. Steel balls 46 of the ball bearing are adapted to engage the outside of tube 34 so that, as the tube 34 is extended or retracted within the tube 33, the balls 46 of the ball bearing will roll, thus reducing the sliding friction. In a similar manner the left end of tube 34 is provided with a ball bearing 47 secured to the tube 34 and having balls 48 adapted to engage the inside surface of the tube 33, thus reducing the sliding friction. Internally within the tube 33 there is provided a stop ring 49 secured to the inside of the tube 33 and adapted to restrict the outward extension by engagement with the ball bearing 47 attached to the tube 34. A similar stop and similar ball bearings may be provided within the ends of the sliding tubes 31 to 35, and 31' to 35'.

Extending through the center of the tubes 31 to 35 there is provided a flexible cable 50 one end of which is attached to the inside end of the core 36, and the other end of which passes around the pulley wheel 42 and subsequently to the rewind mechanism. In a similar manner, a flexible cable 50' passes through the center of tubes 31' to 35' and is secured to the inside end of core 36' passing around pulley 42' and subsequently to the rewind mechanism.

It will be apparent that, as the cable 50 is wound on the rewind mechanism, later to be described, the end of the cable attached to the inside end of the core 36 will be withdrawn toward the trailer 20 and will retract the core 36 into the tube 35 until the end disc 37 engages the end of the tube 35, that the tube 35 thereafter on further movement of the cable will be retracted into the tube 34, tube 34 will be retracted into tube 33, tube 33 will be retracted into tube 32, and finally tube 32 will be retracted into tube 31, until the end disc 37 is substantially flush with

the right side of the trailer 20 in the direction of movement thereof. In a similar manner, the re-winding of the flexible cable 50' will retract the core 36' and the tubes 35' to 32' into tube 31', until the disc 37' is substantially flush with the left side of the trailer. The pulling or reeling in of the flexible cable 50 and 50' can be accomplished in a number of ways, even manually, as will be readily understood.

One mechanical method which gives satisfactory results is shown in Figures 3 and 4, wherein the telescoping arms 39 and 39' have been omitted for the sake of clarity in describing the rewind mechanism. The flexible cable 50, shown in the lower left hand corner of Figure 3, passes around the horizontal pulley 42 as previously described, and thence in a horizontal plane to and around a pulley 55 which is journaled on a shaft fixedly attached to the side wall of the trailer 20. Pulley 55 is located in such a manner that the cable 50 passes over its top and that the center line of the cable is exactly horizontal as it passes around pulley 42. Also mounted on the side wall of the trailer 20 is a pivoting pulley assembly 56 having a hollow support member 57 fixedly attached to the side wall of the trailer 20 and positioned in such a manner that the center line of the cable 50 as it passes around the pulley 55 is parallel with the hollow portion of the support member 57. Journaled on the hollow support member 57 is a hollow pulley bracket 58. This bracket is rotatably mounted on support member 57 in such a manner that the hollow portions coincide. Attached to the bracket 58 in rotatable engagement, there is provided a pulley wheel 59 so positioned that the groove is tangent to the hollow portion in the bracket member 58 and the bracket support member 57.

The pulley assembly 56 is positioned on the side wall of the trailer 20 so that the hollow portions of 57 and 58 are vertical and tangent to the groove of pulley 55 and so that cable 50 will pass from pulley 55 directly through the hollow portions of the bracket support member 57, the bracket 58, and around pulley 59. A similar swivel pulley arrangement 62 is mounted on a movable bar 63. The pulley assembly 62 is comprised of a hollow support member 64, a hollow bracket member 65, and a grooved pulley 66. The pulley assembly 62 is mounted on bar 63 in such a manner that the hollow portions of the bracket member 65 and support member 64 are tangent to and vertically located above rewind drum 80 later to be described. The flexible cable 50 passes around and under pulley 59, over and around pulley 66, through the hollow in the bracket 65 and support member 64, and through a hole 67 provided in sliding bar 63.

The rewind drum 80 is suitably supported on a shaft rotatably journaled on support member 81, and a similar support member (not shown). The rewind drum 80 is provided with a groove 82 spirally cut in the surface of the drum being of a size sufficient to accommodate the cable 50. One end of the cable 50, as previously described, is attached to segment 36 of the telescoping arm 30. The other end of the cable is attached to the groove in the rewind drum by welding, clamping, or the like as at 83. The rewind drum 80 is fixedly mounted on a shaft 84 one end of which has attached thereto a disc portion 85 of a friction drive. As is well known, the face of the friction disc may be covered with a resilient surface 86 composed of leather or the like.

Mounted on the rewind drum 80 is a ring gear 87 adapted to engage a smaller gear 88. Gear 88

is fixedly attached to a threaded shaft 89, journaled to support members 91 and 92. The threaded shaft 89 passes through a threaded portion 93 of the movable bar 63. The movable bar 63 is held in proper operating position by bars 94 and 95 which pass through the movable bar 63, and are attached to support members 91 and 92. The threaded portion of the shaft 89 is provided with threads of a sufficient pitch to maintain the hollow portions of pulley assembly 62 directly over the groove 82 in the rewind drum, taking into consideration the gear reduction obtained by gear ring 87 and small gear 88.

As the rewind drum is rotated in an anti-clockwise direction, gear ring 87 will also rotate in an anti-clockwise direction and thus rotate small gear 88 affixed to threaded shaft 89 in a clockwise direction. It will also be apparent that because of the threaded portion 93 engaging and cooperating with the threaded portion of shaft 89, that as the shaft 89 is rotated in a clockwise direction, the support bar 63 will move along the guide bars 94 and 95 toward the ring gear 87. Thus, the cable 50 will be continuously placed directly over the groove 82 in the rewind drum 80.

It will be apparent that as the sliding bar 63, having attached thereto pulley assembly 62, is moved toward the gear ring 87, the relationship between the pulley assembly 56 and pulley assembly 62 will be continuously changed but, because of the fact that the pulley 59 and pulley 66 are in a swiveling position and also because of the fact that the flexible cable passes through the actual swivel support, the pulley 59 and the pulley 66 will always be parallel and in an operating relation.

The rewind drum 80 is rotated by engagement of the other half 96 of the friction clutch 85. The friction disc 96 is keyed to, but slidably mounted on shaft 97 to which is fixedly attached sprocket wheel 98. The sprocket wheel 98 is driven by sprocket chain 99 through sprocket wheel 100, attached to the shaft 101 of motor 102. The motor 102 is driven by electric power supplied from batteries 103 through wire 104. A suitable switch (not shown) for starting or stopping the motor 102 may be located convenient to the starter or operator of the equipment.

The friction disc 96 is provided with a groove 105 in which is provided a yoke 109 attached to a rod or shaft 110 which may be pivotally mounted at 111. The top portion of the rod or shaft extends through the floor of the trailer and can be seen in Figure 1. The top end of the shaft or rod 110 is bent over to form a handle for more convenient operation of the friction disc 96. If the handle of the rod or shaft 110 is urged in a direction toward the seat 23 of the trailer as seen in Figure 1, the opposite end of the rod will be urged in the opposite direction because of pivot bearing 111, and thus the yoke 109 around the friction disc 96 will urge this disc into engagement with the surface 86 of friction disc 85 thus causing the rewind drum 80 to rotate when the motor 102 is in operation. If the motor and sprocket 100 travels in an anti-clockwise direction, the rewind drum 80 and ring gear 87 will travel in anti-clockwise rotation, and thus gear 88 will travel in a clockwise direction turning the threaded shaft 89. Bar 63 will be moved toward the opposite end of the rewind drum and the cable 50 will be wound into the grooves 82 on the drum 80 and will pull the segments 31 to 36 of the telescoping arm 30 into closed relation.

Attached to the sliding bar 63 is a stock brack-

et 112 positioned in such a manner that when the cable 50 is substantially completely wound, and the disc 37 is substantially flush with the side wall of the trailer 20, the bracket 112 will engage the lower portion 113 of the shaft 110. Further movement of the bracket 112 against the shaft 110 through the yoke 109, will disengage the friction disc 96 and stop further rotation of the rewind drum 80.

In a similar manner flexible cable 50' passes over pulley 55', through and around swivel pulley assembly 56', over and around pulley 62', on to rewind drum 80' provided with a spiral groove 82'. The operation of the rewind drum 80' is accomplished in a similar manner to that described previously. The operation includes the use of ring gear 87', gear 88', threaded shaft 89', friction disc 85', friction disc 96', sprocket wheel 98', yoke 109', bracket 112', shaft 110', and pivot 111'.

The top end of the rod or shaft 110' is bent over to form a handle to facilitate the operation of the disc member 96'. The bent over portions of the shaft handles 110 and 110' is made in such a way that they can be grasped simultaneously with one hand.

It will be apparent that, as the starter or operator urges both rods or shafts toward the seat of the trailer, both drums 80 and 80' will rewind the cables 50 and 50', thus retracting the segments of the telescoping arms 30 and 30' within the confines of the tubes 31 and 31'. If the arm 30 was not extended to the same length as the arm 30', it will be apparent that arm 30 will be retracted to completion before arm 30' is completely retracted, and it will also be apparent that when arm 30 is completely retracted the friction disc 96 will be urged out of engagement with friction disc 85, because of the bracket 112 engaging the lower end 113 of the shaft 110. Thus the handle of the shaft 110 will be urged slightly ahead while pressure may be continued on the handle of shaft 110' until the arm 30' is also completely retracted.

From the above it can be seen that telescoping arm 30, flexible cable 50 and rewind drum 80 operate independently of the telescoping tube 30', flexible cable 50' and rewind drum 80'. Consequently the starting barrier may be operated with the movable carriage at one side of the track and only one telescoping tube barrier extended, and the closing of the telescoping tube barrier, as an example tube assembly 30, is accomplished by activating rod or shaft 110 causing friction disc 96 to engage friction disc 85, thus rotating rewind drum 80. It can also be seen that if, accidentally, rod or shaft 110' is urged backward nothing will happen to rewind mechanism 80' because bracket 112' will engage bottom end 113' of shaft 110' thus preventing engagement of friction disc 96' and friction disc 85'. It will also be seen from the above that because of the independent operation of the rewind mechanisms and the telescoping rods, that one rod as an example, telescoping rod 30, may be extended to its full length while telescoping rod 30' may be extended for a portion of its length and the retraction of the telescoping rods can be activated simultaneously and completely.

From the above it will seem that the starting gate or barrier may be used on any width track or may advantageously be used in such a manner that the contestants are aligned solely behind a telescoping arm and the actual carriage may be over at one side of the track out of the way of the

contestants. As previously stated, the retraction of the telescoping arms 30 and 30' may be accomplished manually or by the mechanism as previously described or they may be retracted utilizing pneumatic principles. Similarly the telescoping arms may be extended manually or by pneumatic or mechanical means.

Thus, Figure 7 shows diagrammatically a simple arrangement for both extending and retracting the telescoping arms by pneumatic control means. For this purpose, the connections between the individual sections 32, 33, etc. and 32', 33', etc. are connected in an air-tight manner by the provision of suitable fluid-tight packings or sealing rings in a manner well known and as indicated in the drawing. The inner tubes or cylinders 30 or 30' are mounted upon the movable carrier in the same manner as described hereinbefore and are each connected to a pressure or vacuum tank 40' or 41', respectively, through control valves 42' and 43', to enable a compressed fluid, such as air or oil to be introduced or withdrawn from the cylinders for extending and retracting the telescoping arms, in a manner readily understood and well known in connection with pneumatically operated telescopic devices of this type. The tanks 40' and 41' may be connected to a compressor or pump, respectively, driven by the motor of the self-propelled vehicle upon which the device is mounted.

Thus, while the mechanical retracting means for the telescoping starting barrier shown in Figures 1 to 6 have an operation, whereby the telescoping arms have to be extended manually, Figure 7 enables both extension and extraction by the control mechanism.

If it is decided to always operate the telescoping arms 30 and 30' simultaneously and to extend these arms at the start to the same degree of extension, the actual rewind mechanism can be materially simplified by winding both the cables 50 and 50' on the same rewind drum 115, as shown in Figure 5.

In the latter, rewind drum 115 is provided with two spirally cut grooves of sufficient size to accommodate the flexible cables and in this case the swivel pulleys 62 and 62' are mounted on a sliding bar 116 which is adapted to slide on fixed shafts 117 and 118. The swivel pulleys are the same as previously described and are so positioned on the sliding bar 116 so as to be properly tangent to the grooves on the rewind drum 115. The rewind drum 115 is provided with a ring gear 119, a small gear 120 fixedly attached to a threaded shaft 121 which is journalled in suitable supports such as previously described in connection with threaded shaft 89 of Figure 3. Threaded shaft 121 is adapted to engage a threaded portion or collar 122 attached to the slide bar 116.

The operation of the rewind mechanism of Figure 5 is similar to that previously described. Friction clutch 96 is urged into engagement with friction disc 85 by means of yoke 109, fitted in groove 105 and attached to a shaft which extends above the floor of the carriage. Friction clutch 96 is rotated by a motor (not shown) turning rewind drum 115 and ring gear 119 in an anti-clockwise direction and gear 120 is thus rotated in a clockwise direction rotating threaded shaft 121 and pulling bar 116 toward ring gear 119. The threads on shaft 121 are provided with the proper lead so as to pull bar 116 at the correct rate to properly position

swivel pulleys 62 and 62' always over their respective rewind grooves.

A similar bracket to 112 of Figure 3 may be mounted on the slide bar 116 if desired, however this top bracket is not absolutely essential as when the cables 50 and 50' have been completely rewound, the friction disc 86 will continue to rotate against friction disc 86 until the clutch is disengaged manually. The time for releasing the clutch mechanism can be visually observed as the telescoping arms become flush with the sides of the carriage.

While the invention has been described as being mounted in an automobile trailer, it will be apparent that the starting barrier may be built in, or mounted on any self-propelled vehicle. Thus, in Figure 2B, the telescoping arms 30 and 30' and control mechanism therefore are shown directly mounted upon the rear of an open or convertible motor car 28 or 28', other details of the construction and operation being substantially the same as described hereinbefore.

The preferred operation of the starting barrier described consists of manually extending the telescoping arms 30 and 30', while the contestants are aligning themselves in the rear of the starting barrier, moving the barrier at a gradually increasing rate of speed until the contestants are satisfactorily aligned behind the barrier, maintaining the contestants aligned until they have crossed the starting line, and thereafter speeding up the mobile unit, engaging the clutch to start the rewind mechanism thus retracting the telescoping arms and subsequently guiding the carriage or mobile unit over to the side of the track out of the way of the contestants.

It will be apparent that there are numerous modifications to the broad underlying principles of the invention and that the specification and drawings should be considered as descriptive and not limiting the broad scope and spirit of the invention as defined in appended claims.

I claim:

1. In a device for aligning and starting contestants of speed in motion of the type comprising a movable carrier and a starting barrier mounted thereon and actuatable to and from operative position, said barrier comprising at least one telescopic arm having a plurality of cooperating hollow sections and mounted upon said carrier in a substantially horizontal position and transversely to the longitudinal axis of said carrier, whereby said arm may be variably extended at right angle to the direction of movement of said carrier, and actuating means upon said carrier for retracting said arm into collapsed position.

2. In a device for aligning and starting contestants of speed in motion of the type comprising a movable carrier and a starting barrier mounted thereon and actuatable to and from operative position, said barrier comprising a pair of telescoping arms mounted upon said carrier closely adjacent and parallel to each other and in a substantially horizontal position and transversely to the longitudinal axis of said carrier, whereby said arms may be variably extended in opposite directions and at right angles to the direction of movement of said carrier, and actuating means upon said carrier for retracting said arms into collapsed position.

3. In a device for aligning and starting contestants of speed in motion of the type comprising a movable carrier and a starting barrier mounted thereon and actuatable to and from

operative position, said barrier comprising a pair of telescoping arms mounted upon said carrier closely adjacent and parallel to each other and in a substantially horizontal position and transversely to the longitudinal axis of said carrier, whereby said arms may be variably extended in opposite directions at right angles to the direction of movement of said carrier, and actuating means upon said carrier simultaneously retracting both said arms into collapsed position.

4. In a device for aligning and starting contestants of speed in motion of the type comprising a movable carrier and a starting barrier mounted thereon and actuatable to and from operative position, said barrier comprising a pair of telescoping arms mounted upon said carrier closely adjacent and parallel to each other and in a substantially horizontal position and transversely to the longitudinal axis of said carrier, whereby both said arms may be variably extended in opposite directions at right angles to the direction of movement of said carrier, and actuating means upon said carrier separately and independently retracting said arms into collapsed position.

5. In a device for aligning and starting contestants of speed in motion of the type comprising a movable carrier and a starting barrier mounted thereon and actuatable to and from operative position, said barrier comprising at least one telescoping arm having a plurality of cooperating sections and mounted upon said carrier in a substantially horizontal position and transversely to the longitudinal axis of said carrier, whereby said arm may be variably extended at right angle to the direction of movement of said carrier, and actuating means upon said carrier for extending and retracting said arm.

6. In a device for aligning and starting contestants of speed in motion of the type comprising a movable carrier and a starting barrier mounted thereon and actuatable to and from operative position, said barrier comprising at least one telescoping arm having a plurality of cooperating sections and mounted upon said carrier in substantially horizontal position and transversely to the longitudinal axis of said carrier, whereby said arm may be variably extended at right angle to the direction of movement of said carrier, winding drum means upon said carrier, a cable passing through said arm having one end attached to the outermost section of said arm and having its opposite end secured to said drum, and guide means to wind said cable upon said drum, for retracting said arm from extended to collapsed position.

7. In a device for aligning and starting contestants of speed in motion comprising a movable carrier and a starting barrier mounted thereon and actuatable to and from operative position, said barrier comprising at least one telescoping arm having a plurality of cooperating sections and mounted upon said carrier in substantially horizontal position and transverse to the longitudinal axis of said carrier, whereby said arm may be extended at right angle to the direction of movement of said carrier, a rotatable winding drum upon said carrier, a flexible cable passing through said arm having one end secured to the outermost section of said arm and having its opposite end secured to said drum, guide means for said cable, and means for relatively axially moving said drum and guide means while said drum is rotated, to wind said cable upon said

drum in adjacent turns, to thereby retract said arm from its extended to its collapsed position.

8. In a device for aligning and starting contestants of speed in motion of the type comprising a movable carrier and a starting barrier mounted thereon and actuatable to and from operative position, said barrier comprising a pair of telescoping arms mounted upon said carrier in a substantially horizontal position and transversely to the longitudinal axis of said carrier, whereby said arms may be extended in opposite directions and at right angle to the direction of movement of said carrier, a pair of rotatable winding drums upon said carrier with means for simultaneously rotating the same, flexible cables passing through said arms each having one end secured to the outermost section of one of said arms and having its opposite end secured to one of said drums, guide means for each of said cables, and means for relatively axially moving the respective guide means and drums during rotation of the latter, to wind said cables upon said drums

in adjacent turns, to thereby retract said arms from the extended to the collapsed position.

OCTAVE BLAKE.
